(57) **CLAIM**

I claim the ornamental design of a cornice soffit panel, as
shown and described.

DESCRIPTION

FIG. 1 is a top view of an embodiment of a cornice soffit panel.

FIG. 2 is a bottom view of the cornice soffit panel of FIG. 1.
FIG. 3 is a left side view of the cornice soffit panel of FIG. 1.
FIG. 4 is a right side view of the cornice soffit panel of FIG.
1.

FIG. 5 is a rear view of the cornice soffit panel of FIG. 1.
FIG. 6 is a front view of the cornice soffit panel of FIG. 1.
FIG. 7 is a top view of another embodiment of a cornice soffit
panel.
FIG. 8 is a bottom view of the cornice soffit panel of FIG. 7.
FIG. 9 is a left side view of the cornice soffit panel of FIG. 7.
FIG. 10 is a right side view of the cornice soffit panel of FIG.
7.

FIG. 11 is a rear view of the cornice soffit panel of FIG. 7.
FIG. 12 is a front view of the cornice soffit panel of FIG. 7.
FIG. 13 is a top view of another embodiment of a cornice
soffit panel.

FIG. 14 is a bottom view of the cornice soffit panel of FIG. 13.
FIG. 15 is a left side view of the cornice soffit panel of FIG.
13.
FIG. 16 is a right side view of the cornice soffit panel of FIG.
13.
FIG. 17 is a rear view of the cornice soffit panel of FIG. 13.
FIG. 18 is a front view of the cornice soffit panel of FIG. 13.
FIG. 19 is a top view of another embodiment of a cornice
soffit panel.
FIG. 20 is a bottom view of the cornice soffit panel of FIG. 19.
FIG. 21 is a left side view of the cornice soffit panel of FIG.
19.
FIG. 22 is a right side view of the cornice soffit panel of FIG.
19.
FIG. 23 is a rear view of the cornice soffit panel of FIG. 19;
and,
FIG. 24 is a front view of the cornice soffit panel of FIG. 19.
Broken lines do not form part of the claimed design.
